UNITED STATES PATENT OFFICE.

FERDINAND MORA CANDA, OF NEW YORK, N. Y.

ROLL FOR ROLLING MILLS.

Application filed December 17, 1920. Serial No. 431,465.

To all whom it may concern:

Be it known that I, FERDINAND MORA CANDA, a citizen of the United States, residing at No. 162 West 54th Street, New York, N. Y., have invented a new and useful Improvement in Rolls for Rolling Mills, of which the following is a specification.

My invention relates to rolls for metal rolling mills and while particularly intended for use in ball rolling machines, may also serve other purposes.

In the operation of rolling mills it is important to maintain the operating faces or surfaces of the rolls accurate and true and the necessity for frequent trueing of the rolls adds considerably to the expense of maintenance. In the type of rolls having ridges to shape the material, wear of these ridges is particularly undesirable. Accordingly, I construct those portions of the roll, which are mainly subject to wear, of very hard steel. It frequently happens that one or more of the ridges become worn or defective while the remainder of the roll is perfect. I have, therefore, devised a roll in which each ridge portion is separately formed and may be removed or replaced and by so doing the life of the roll is very greatly lengthened. Moreover this change of parts can be effected quickly so that the loss of time heretofore necessitated by trueing of the rolls is greatly reduced and the expense of replacing a worn or partially defective roll with an entire new one is obviated.

The object of my invention, therefore, is to reduce the wear of rigid rolls and thus to prolong their life, and to provide for the ready replacement of only those portions of the roll which become worn or defective.

In the accompanying drawings, Figure 1 is a longitudinal sectional view of a mill roll embodying my invention, the section being taken on the line 1—1 of Fig. 3; Fig. 2 is a longitudinal sectional view on the line 2—2 of Fig. 4, showing another form of my invention; Figs. 3 and 4 are transverse sectional views on the lines 3—3 of Fig. 1 and 4—4 of Fig. 2, respectively.

I construct the roll of a series of rings or disks which are bolted together and secured in any suitable manner upon the roll shaft. In the form shown in Fig. 1 the sharp ridges of the roll are formed on the peripheries of narrow disks 5 of a very

hard grade of steel, such as tool steel and which may be one of the steels known in the trade as "high-speed tool steel." The troughs of the grooves are formed upon wider disks 6 interposed between the disks 5 and formed of a tougher metal, preferably unhardened forged steel. All of the disks are provided with perforations to receive the bolts 8 after they have been assembled on the shaft which is of mild steel and to which they are locked by a key 12.

Under some conditions I found that I may dispense with the forged steel disks 6 and form the rolls entirely from disks of specially hard grade steel, constructing the disk with oppositely disposed curves symmetrically arranged to form central ridges, each groove being formed by the curves of adjacent disks. I have illustrated this construction in Fig. 2 wherein the entire roll is formed of a very hard grade of steel disks 5^a, each disk being the width of one of the grooves. The disks are assembled on the shaft and bolted together in the manner described in connection with the form shown in Fig. 1.

I have illustrated rolls which are suitable for use in ball rolling mills such as shown in my applications for Letters Patent, Ser. No. 329,774, filed Oct. 10, 1919, Ser. No. 332,284, filed Oct. 21, 1919, and Ser. No. 334,030, filed Oct. 28, 1919. It will be evident that my method of constructing rolls may be applied to other types, as for instance, such rolls having V-shaped grooves which are used for rolling angle bars, particularly the so-called "square root" angle bar.

As previously stated, the rolls are especially intended to be used in machines for forming steel or other iron bars adapted for use in crusher mills and the like. The blanks supplied to the machine are usually in the form of rods, these blanks being preferably heated to a suitable forging or rolling temperature before they pass through the machine. When the bar is pressed against the rolls, the sharp projecting ribs or ridges cut into the bar forming grooves which divide it into sections, each corresponding to one of the grooves of the rolls. As the operation proceeds, the ribs cut more deeply into the bar and the metal at the shoulders of the sections into which the said bar is divided is pressed inward toward the equatorial portions of the forming

balls. It is evident that the greatest strain and wear in this operation falls upon the outer peripheral ribs or ridges of the rolls which are required to continually cut or groove the blank bar. I have found that these ribs will maintain their integrity and accurate shape for a considerable length of time if they are formed of a very hard steel such as the "high speed" alloy steels and provided they are so disposed that the strains will be symmetrical and uniformly distributed at the base of the ribs in the supporting metal. I accomplished this purpose by forming the ribs symmetrically upon a central plane of the disk. When the disks have been rigidly bolted together upon the shaft they mutually brace each other against lateral thrusts, and form, in effect, a solid roll. At the same time any disk which becomes defective from wear, chipping or breakage may be readily removed and replaced with a new disk, thereby greatly prolonging the normal life of the entire roll, very materially reducing the expense of maintenance as well as sav-

ing the time which has heretofore been lost in frequent trueing of the rolls.

I claim:

1. A grooved rolling mill roll, comprising a plurality of disks detachably secured together, certain of said disks being formed of a hard grade of steel and having a centrally disposed peripheral rib forming by converging surfaces, the inner edges of which merge into the curved faces of adjacent disks of tougher metal. 30 35

2. A rolling mill roll, comprising a grooved roll body formed of juxtaposed symmetrically shaped disks, certain of said disks being composed of a hard grade of steel and provided with centrally disposed peripheral ribs whose opposite sides conform to the curvature of the grooves of the roll body, each groove extending over a plurality of disks. 40 45

In testimony whereof, I have signed my name to this specification, this 16th day of December, 1920.

FERDINAND MORA CANDA.
